W. HOUGHTON.

SHEAVE BLOCK.

APPLICATION FILED AUG. 19, 1920.

Patented Feb. 14, 1922.

Inventor:

Willard Haughton

FIG. 4 By his Attorney

Attorney
Derrick Barnes

UNITED STATES PATENT OFFICE.

WILLARD HOUGHTON, OF SEATTLE, WASHINGTON.

SHEAVE BLOCK.

1,406,560.

Specification of Letters Patent. Patented Feb. 14, 1922.

Application filed August 19, 1920. Serial No. 404,584.

To all whom it may concern:

Be it known that I, WILLARD HOUGHTON, a citizen of the United States, residing at Seattle, in the county of King and State of Washington, have invented certain new and useful Improvements in Sheave Blocks, of which the following is a specification.

This invention relates to sheave-blocks. The object of my improvements is to produce a block of this character which is especially applicable for use as a snatch-block which should be of light weight, strong, durable, have as few parts as possible and be constructed to obviate any accidental dislodgement of the hauling or hoisting rope.

A further object of the invention is the provision in a block of improved devices for lubricating the sheave through the medium of a series of ducts and grease receptacles which are readily replenished with grease or an equivalent.

The invention consists in the novel construction, arrangement and combination of parts as will be hereinafter described and claimed.

In the accompanying drawings, Figure 1 is a plan view of a block embodying my invention. Fig. 2 is a similar view, partly in horizontal section, a portion of the upper cheek member broken away, said member being illustrated in its detachable position.

Fig. 3 is a sectional view through 3—3 of Fig. 2, with the upper cheek member, shown separated with respect to the other parts of the block.

Fig. 4 is an edge view of the sheave.

In carrying out the invention, I provide a lower cheek member 5 having an upwardly extending post element 6 which serves as the spindle for a sheave 7 and an upper cheek member 8 which is coupled to said lower cheek member to afford a housing for said sheave.

One end of each of said cheek members is of a substantially circular form having a diameter slightly greater than the diameter of the sheave and with its arcuate periphery concentric to the spindle axis. The other ends 5¹ and 8¹ of the respective cheek members are each of a corresponding substantially triangular shape.

Integral with the cheek member 5 and extending upwardly from it near the extremity of the part 5¹ thereof is a spacing element 9 having an inwardly directed tongue 10 of

a length equal to the width of the element 9, or nearly so.

Integral with the cheek member 8 and extending downwardly therefrom is a spacing element 11 located to have its outer surface 12 fit against the shoulders 13 of the element 9 when the cheek members are in the operative positions in which they are represented in Fig. 1. The spacing element 11 is moreover provided with a horizontal groove 14 to accommodate the tongue 10 of the element 9.

The two elements 9 and 11 are of the same widths and the inner side of the element 11 is rounded as at 15 to obviate the chafing of a strain-rope or cable 16 in an eye 16¹ of which said elements are engaged.

The upper end of the post 6 extends through a bored aperture 17 provided in the cheek member 8, said post and the upper portion of the bore 17 are screw threaded as at 6¹ and 17¹, respectively, in such a manner that they will interengage when the cheek piece 8 occupies approximately the position in which it is represented by broken lines 8^a in Fig. 1 and by full lines in Fig. 2. Said screw threads are furthermore adapted to have the cheek member 8, when swung about the axis of the post in the direction of arrow A in Fig. 1, screwed down upon the post to enable the groove 14 to receive the tongue 10. The sheave 7 is represented as having hubs 19 which fit within annular recesses 20 and 21 provided in the respective cheek members.

Said sheave is formed to provide in its upper face a plurality of grease receptacles 22 which communicate by ducts 23 with journal of the sheave. Inverted cups 24 inserted in the respective receptacles serve as covers for the latter and are removable by a knife blade or the like when the receptacles are to be charged with grease. The post 6 is made hollow to also serve as a grease receptacle 26, the same being closed by a screw 100 plug 25. The outlet 27 for receptacle 26 extends through that side of the post which is diametrically opposite to the side of the sheave about which the hauling cable 28 passes.

From the foregoing it is apparent that the rope 16 when looped about the cheek elements 9 and 11 serves to retain the block in operative position. To detach the rope 28 the rope 16 is shifted away from said cheek ele- 110

ments as shown for example in Fig. 2, whereupon the upper cheek member may be swung around into the position denoted by broken lines 8^b in Fig. 1 to enable the rope 28 to be taken out through the opening thus provided.

By reason of its strong and rigid construction, the facility of removing the hauling cable or rope, its light weight, and the impossibility of the block being opened when under strain, the invention is peculiarly adapted for use in logging operations as a snatch block.

What I claim is,—

15 In a block of the character described, the combination with a holding rope, a sheave, and a spindle for the sheave, of a frame for said sheave, said frame comprising an upper

and lower cheek member, a spacing block carried by the extreme forward end of the lower cheek member, said spacing block provided with an inwardly directed tongue, and a spacing block carried by the forward end of the upper cheek member having a groove in its upper surface for reception of the said inwardly directed tongue of the first mentioned spacing block, the said holding rope adapted to surround the spacing blocks whereby the said cheek members are releasably held in operative positions.

Signed at Seattle, Washington, this 13th day of August, 1920.

WILLARD HOUGHTON.
